UNITED STATES PATENT OFFICE

ALVIN G. SHERMAN, OF GROSSE POINTE, MICHIGAN, ASSIGNOR TO THE DETROIT VAPOR STOVE COMPANY, OF DETROIT, MICHIGAN, A CORPORATION OF MICHIGAN

STOVE CONSTRUCTION

Application filed February 7, 1927. Serial No. 166,382.

This invention relates to stove construction, and has for its object an improved enamelling stove structure, providing what is believed to be a novel idea in making the 5 enamel parts, most liable to damage, easily replaceable.

Glass enamelled stoves have come into vogue and cooking stoves are now made which have practically all the surfaces thereof 10 enamelled. Attempts have been made to enamel the entire oven front frame, but such attempts have not been successful for the reason that the space between the broiler and oven has quickly become stained and 15 cracked, and very unsightly. In order to overcome such defects it has heretofore been necessary to replace the entire oven front frame, which is a very expensive proposition, due both to the cost of material and time of 20 replacement. My present invention is directed to provision of the one-piece oven front frame, the entire surface of which may be enamelled, and which is provided with small, removable parts at those points most 25 susceptible to damage.

In the drawings:

Fig. 1 is a fragmentary perspective showing the removable facing strip below the oven opening.

Fig. 2 is a perspective of this strip.

Fig. 3 is a section taken on the line 3—3 of Fig. 1.

Fig. 4 is a rear elevation of the structure between the oven and the broiler chamber on 35 the inside.

Fig. 5 is a section on the line 5—5 of Fig. 4.

Fig. 6 is a section on the line 6—6 of Fig. 4.

Fig. 7 is a fragmentary enlarged perspective, showing how the facing strip and the 40 oven come together.

a designates the stove structure which forms the upper oven and the lower broiling chamber in accordance with common practice. A door *b* acts as a closure for the oven, 45 and a door *c* for the broiling chamber. The front frame *d* is usually either a casting or a pressed metal member which is ordinarily not glass enamelled even in those stoves which affect to be enamelled. The reason for this 50 is that this frame is exposed to considerable

heat, and also the drippings of things boiling over on the oven flowing out on the frame. It has, therefore, been found that the glass enamelling of this frame is not attended with successful service as the enamel 55 coating becomes crazed, fractured and stained, especially immediately under the oven where the heat is considerable, and where cooking materials boil over on the same, and often stain and crack. This is 60 especially true where this enamel becomes extremely hot and cold when things are spilled over it. This will cause the enamel to craze and fracture.

Due to these causes some of the stove builders have found it advisable to use a plain metal front frame or a nickel frame. However, I have discovered that the difficulty may be largely remedied by constructing the front frame so as to afford an easily replaceable 65 enamel oven threshold facing strip. That is, when in the course of usage the enamel becomes checked, or broken or stained, another strip may be easily installed at a very small 70 cost. This enables the entire front of the 75 stove to be enamelled in accordance with the general plan, and adds very much to the clean, neat appearance of the stove.

To accomplish this purpose, we use a pressed metal front frame *d* which is glass 80 enamelled all over, preferably with three coats, to wit: the usual blue ground coat and two finishing coats of white enamel. The entire frame front and back is provided with the blue coat which is applied by dipping. Only 85 the front of the frame is provided with the white coats which are sprayed on. Preferably the center bar *e* has the regular blue ground coat of enamel, and then the face of the bar at the bottom has also two coats of 90 white enamel, as is indicated in Fig. 5.

There is arranged to be bolted over this a removable facing strip for the oven threshold. This is designated *f*. Studs *g* are welded on the inside and these serve to clamp 95 the asbestos insulating strip *h* and the replaceable facing strip to opposite sides of the center bar of the frame. This asbestos insulation on the inside of the center bar helps very materially to arrest the transfer of the 100

heat to the front of the center bar so that it will not craze the enamel of the center bar. This heat insulating strip is, therefore, also useful in protecting the enamel on the center bar itself as well as the enamel on the removable facing strip of the threshold. It will be apparent that the same idea can be carried out in connection with the other parts of the stove that are subjected to the same 10 enamel deteriorating conditions.

The center bar *e* has the portion 1 which is offset from the front frame *d* owing to the pressed-in portion 2. The ends of the facing strip *f* form flush joints with the front frame 15 *d* as at 3 as shown in Figs. 1, 3, and 7. The depression 4 above, and the depression 5 below, the facing strip *f*, as shown in Figs. 5, 6, and 7 form seats for the oven doors.

What I claim is:

20 1. In a stove, a glass enamel front frame having a center bar with an offset portion dividing the oven and broiler chamber, a removable threshold facing strip arranged to fit nicely in said offset portion flush with the 25 end portions of said center bar so that the facing strip and the end portions of the center bar are in the same plane.

2. In a stove, a glass enamel front frame having a center bar with an offset portion dividing the oven and broiler chamber, a removable threshold facing strip having longitudinal flanges arranged to fit nicely in said offset portion flush with the end portions of 30 said center bar to permit an air space between the center bar and the removable facing strip.

3. In a stove, a front frame having a center bar with an offset portion dividing the oven and broiler chamber, a removable threshold facing strip arranged to fit nicely in said 40 offset portion flush with the end portions of said center bar, and studs on the inside of said facing strip for clamping said facing strip to said offset portion of the center bar whereby a smooth exterior face on the facing strip is permitted.

45 In testimony whereof I have affixed my signature.

ALVIN G. SHERMAN.
